UNITED STATES PATENT OFFICE.

WILLIAM VIRGIL JORDAN AND THOMAS MARSHALL SWANK, OF LOUISVILLE,
KENTUCKY.

ENGINE.

Application filed November 26, 1923. Serial No. 677,101.

To all whom it may concern:

Be it known that we, WILLIAM VIRGIL JORDAN and THOMAS MARSHALL SWANK, both citizens of the United States, and residents of Louisville, in the county of Jefferson and State of Kentucky, have invented a new and useful Improvement in Engines, of which the following is a full, clear, and exact description.

10 Our invention relates to improvements in engines, more particularly to a novel valve controlling mechanism for steam engines, and it consists in the combinations, constructions, and arrangements herein described and claimed.

An object of our invention is to provide a device by means of which the stroke of the slide valves associated with a plurality of cylinders may be simultaneously regulated so as to admit a predetermined amount of steam to the cylinders.

A further object of our invention is to provide a device of the type described, which may be operated even while the engine is running, thereby obviating the necessity of stopping the engine to adjust the travel of the valves.

A further object of our invention is to provide an engine having a novel form of cross-head guide so arranged as to consume a minimum amount of energy in friction.

A further object of our invention is to provide an engine of the V-cylinder type arrangement, in which the valve stroke control mechanism is enclosed in the crank case, thereby insuring efficient lubrication, and also the protection of the working parts.

Other objects and advantages will appear in the following specification, and the novel features of the invention will be particularly pointed out in the appended claims.

Our invention is illustrated in the accompanying drawings, forming part of this application, in which

45 Figure 1 is a plan view of an engine constructed according to our invention,

Figure 2 is a section along the line 2—2 of Figure 1,

50 Figure 3 is a section along the line 3—3 of Figure 1,

Figure 4 is an enlarged section along the line 4—4 of Figure 2,

Figure 5 is a section along the line 5—5 of Figure 4,

Figure 6 is a side view of one of the cross-head guides,

Figure 7 is a diagrammatic view showing the ports in the steam chest, and

Figure 8 is a diagrammatic view showing a slide valve.

In carrying out our invention, we provide a support 1 having an opening 2 therein, arranged to receive the bottom 3 of the crank case. The crank case proper is made preferably of a casting, and is provided with portions 4 which rest upon the support 1 (see Figures 2 and 3). Adjacent to the portions 4 and integral therewith are portions 5, which are inclined and which form the parts to which the cylinders are secured. An integral cover or top portion 6 connects the portions 5, as will be seen from the drawings. In the drawings, we have shown a pair of opposed cylinders angularly disposed with respect to one another, as in the V type, but offset to permit connection to a common crank shaft.

In Figure 2, it will be observed that the cylinders 7 and 8 are secured to the portions 5 by means of rods 9 which pass through extensions or flanges 10 of the cylinders. Each cylinder is closed at its outer end by heads 11, which are screwed in place. The opposite end of the cylinder has a head 12, and a stuffing box 13 connected thereto. The pistons 14 are connected by piston rods 15 with a cross-head 16. The construction of this cross-head is best shown in Figure 5. It will be seen that it comprises a block 16 having a wrist pin 17 extending therethrough. This wrist pin is mounted in roller bearings 18. The piston rod is forked at its end to straddle the pitman 19, and the forked ends of the piston rods are pinned to the wrist pin, as shown in Figure 4. The block 16 slides in a guide member shown in Figure 6. This cross-head guide consists of a body portion 20 having a head or end plate 21, and it is provided with arms 22 having guide strips 23 on which the block 16 slides, as shown in Figure 5. The arm 22, as will be seen from Figure 2, passes through an opening in the portion 5 of the crank case, and the plate 21 is held in position by means of sleeves 24 which surround the rods 9, thus holding the cross-head guides rigidly in position.

It will be understood that the cylinder

and the steam chest form an integral casting. In Figure 3 we have shown a steam chest containing the valves 25, with the inlet and exhaust ports 26 and 27 respectively. The valve 25 is connected by a valve rod 26' which passes through the plate 21 and the portion 5, and is pivotally connected at 28 with a lever 29 having a curved slot 30 therein. Each of the levers 29 is pivoted 10 on the opposite side of the center line through the crank shaft at 31. On the crank shaft 32 are a pair of eccentrics 33 which are connected by rods 34 with heads 35, disposed in the respective slots 30 of the levers 29. These heads 35 are connected by links 36 with a lever 37, which is mounted on a shaft 38, to which a handle 39 is connected.

From the foregoing description of the various parts of the device, the operation thereof may be readily understood. Steam is admitted to the steam chest and passes into the cylinders 7, driving the pistons 14 in the usual manner. The movement is 20 transmitted to the cross-head 16 which slides in the cross-head guides 22, and through the pitman 19 to the crank shaft 32. The latter is provided with ball bearings at its connection with the pitman 19, and also 25 within the crank case. The movement of the crank shaft 32 causes a reciprocatory movement of the eccentrics 33, and consequently 30 an oscillating movement of the levers 29. This in turn, imparts a reciprocatory movement 35 to the valve rods 26', and causes the movement of the valves 25 to control the admission and the exhaust of the steam.

In Figure 3, when the rods 34 are in the 40 position indicated in full lines, they will give a greater movement of the valve than in the dotted line position. In the latter position there is a minimum of movement. As the arms 34 are moved away from the dotted line position, the movement imparted 45 to the valves is increased. Thus in Figures 7 and 8, if the line X in Figure 8 indicates the full width of the passage in the valve 25, this passage would connect the port p' and the exhaust port e , when the valve is in the 50 position shown in dotted lines. This would occur when the arms 34 are thrown farthest away from the dotted line position, shown in Figure 3. The port p would be taking in the full amount of steam. If now the 55 handle 39 is moved so as to bring the arms

34 in Figure 3 to the dotted line position, then the valve would have been moved to its full line position, shown in Figure 7, and instead of opening the ports p' and p fully, it would only open them partially, thus 60 letting less steam in. Now there are certain conditions in which it is very advantageous to regulate the admission of steam to the cylinder, other than by the throttle. Thus, where the load is such that it could be operated by a reduced amount of steam, the valves may be adjusted so that this will be effected. Since the exhaust is always fully open at the end of the throw of the valve, the result is that there is a decrease of back 65 pressure, and the engine is run more economically.

The provision of removable cross-head guides adds to the simplicity and economical manufacture of the engine, and it also provides an efficient means for lubrication, since it will be observed that the cross-head guides extend into the crank case, where they can be virtually bathed in oil, as for instance, by a splash system.

We claim:

1. In an engine, a crank case, a cylinder disposed externally of said crank case, a removable cross head guide having a portion extending into said crank case, a piston in said cylinder, a piston rod, a cross head secured to said piston rod and arranged to reciprocate on said cross head guide within said crank case, and means for securing said cylinder and said removable cross head 85 guide to said crank case, said securing means also serving a spacing means for spacing said cylinder from said cross head guide.

2. In an engine, a crank case having an opening in the wall thereof, a closure for said opening, said closure extending into the crank case and constituting a cross head guide, a cross head arranged to reciprocate on said cross head guide, a cylinder, a piston within the cylinder, a piston rod connecting said piston with said cross head, spacing sleeves disposed between said cylinder and said closure, and bolts arranged to pass through said spacing sleeves for securing said cylinder at a spaced distance from said closure, and for locking said closure to the crank case wall.

WILLIAM VIRGIL JORDAN,
THOMAS MARSHALL SWANK.
